UMBRELLA LOCKING DEVICE

Wilhelm Staby, Munich, Germany

Application August 31, 1933, Serial No. 687,666
In Germany September 21, 1932

2 Claims. (Cl. 135—44)

Umbrella locking devices are known, in which a sleeve-shaped catch acted upon by a spring is loosely mounted on the slide sleeve holding the inner ends of the stays, and the ends of the ribs 5 carry hooks which can engage the catch when pressed against the same after the closing of the umbrella. In the case of these known umbrella locking devices the catch must be pulled back slightly against the action of its spring when 10 opening the umbrella, and the ribs must then be slightly spread by hand so that, when the slide sleeve and catch sleeve are subsequently shifted, the hooks do not again engage in the catch sleeve and prevent the opening of the umbrella.

15 This invention relates to an improvement of this umbrella locking device and attains the novel effect that, by shifting the slide sleeve and the catch sleeve against the action of the spring, the ribs are released by the catch and immediately thereafter the spreading of the ribs and 20 the opening of the umbrella takes place in a single operation. Moreover, means are provided on the ribs for preventing the ribs from turning after the closing of the umbrella and during the pressing of the hooks of the ribs into the catch.

25 An embodiment of the invention is illustrated by way of example in the accompanying drawing in which:—

Fig. 1 is a longitudinal section through the locking device.

Fig. 2 is a cross-section on line II—II of Fig. 1.

A sleeve 2 is slidably mounted on an umbrella stick 1, and the inner ends of the stays 4 of the umbrella frame are pivotally connected to a rim 3 on the inner end of the sleeve 2, whereas the outer ends of these stays are connected to the ribs 6 by hinges 5. A handle 8 and a sleeve-shaped catch 9 are slidably mounted on the sleeve 2, and a pressure spring 10 is fitted between the catch 9 and the rim 3 of the sleeve 2, so that this spring presses the catch 9 against the handle 8 and this latter against a flange 11 on the outer end of the sleeve 2. The sleeve-shaped catch 9 has on its end bearing against the spring 10 a U-shaped annular flange 12 the open side of which is directed towards the umbrella handle. Each rib 6 has adjacent its outer end a hook 7 extending radially towards the longitudinal axis of the umbrella stick and open towards the point of the umbrella. This hook is provided with an inclined inner edge 13, so that, when the umbrella is closed, this edge bears against the lower edge of the flange 12 of the catch and, when the hooks are pressed against the catch, forces the catch under the action of its spring 10 in the direction towards the umbrella point, so that the hooks 7 spring away from the handle and engage behind the edge of the U-shaped flange 12 of the catch. In order to prevent the ribs from twisting and preventing

an engagement of the hooks, a small strap 14 is provided on each rib adjacent the hooks and projecting from both sides of the rib so that its projecting ends form an arc the curvature of which is adapted to the outer circumference of 65 the U-flange 12 of the catch. These straps 14 bear against the circumference of the U-flange of the catch and prevent the ribs from turning, they are preferably made of resilient material.

In order to open the umbrella, the handle 8 is 70 pushed towards the umbrella point. The handle 8 first shifts the catch 9, which presses on the spring 10 and this latter acts against the rim 3 of the slide sleeve 2. Owing to the yielding of the spring 10 the edge of the U-flange on the 75 catch 9 is disengaged from the hooks 7 and the spreading of the ribs 6 and the opening of the umbrella can take place in a single operation.

I claim:—

1. An umbrella locking device, comprising in 80 combination with the stays, the ribs of the frame and the handle and stick of the umbrella, hooks, one on the outer end of each of said ribs open towards the point of said stick, a slide sleeve loosely mounted on said stick, a sleeve-shaped 85 catch loosely mounted on said slide sleeve, and a U-shaped flange open towards said handle and adapted to engage said hooks, a rim on the inner end of said slide sleeve, and hingedly connected to said stays, a flange on the outer end of said 90 slide sleeve, a handle loosely mounted on said slide sleeve between said outer flange and said catch, and a spring on said slide sleeve between said catch and said inner rim.

2. An umbrella locking device, comprising in 95 combination with the stays, the ribs of the frame and the handle and stick of the umbrella, hooks, one on the outer end of each of said ribs open towards the point of said stick, a slide sleeve loosely mounted on said stick, a sleeve-shaped 100 catch loosely mounted on said slide sleeve, and a U-shaped flange open towards said handle and adapted to engage said hooks, straps, one on each of said ribs adjacent said hook and having laterally projecting ends adapted to bear 105 against said U-shaped flange to prevent a twisting of said ribs, a rim on the inner end of said slide sleeve, and hingedly connected to said stays, a flange on the outer end of said slide sleeve, a handle loosely mounted on said slide sleeve between said outer flange and said catch, and a spring on said slide sleeve between said catch and said inner rim.

WILHELM STABY.
